UNITED STATES PATENT OFFICE

SPENCER HEATH, OF BALTIMORE, MARYLAND, ASSIGNOR TO THE AMERICAN PROPELLER COMPANY, OF BALTIMORE, MARYLAND, A CORPORATION OF MARYLAND

BLADE FOR WINDMILL IMPELLERS

Application filed August 30, 1928. Serial No. 303,025.

This invention relates to impeller blades for windmills and has for its principal object the production of impeller blades of unitary structure without articulated parts but having the property of changing their form advantageously in response to varying degrees of wind-force acting upon them. With this and further objects in view I have invented the improved blade, one form 10 of which is set forth upon the accompanying drawing, in which:

Figure 1 is a plan view of an impeller with two blades 1 and 2;

Figures 2 and 3 are elevations of blades 15 1 and 2 of Figure 1; and

Figures 4 and 5 are cross sections on the lines 4—4 and 5—5 of Figure 1 respectively enlarged.

In the form here illustrated two blades 20 are employed but any number or a single blade may be used; in the latter case some firm of counterbalance should be used with the single blade.

For the purposes of this invention the 25 blades may be of wood, metal, paper or other composition, solid or hollow preferably protected by metal sheathing on those portions most exposed to wear and covered with protective coating to resist moisture and corrosion or other weathering effects of exposure.

In the drawing the blades are given the numerals 1 and 2 and the hub upon which they center and are carried is given the 35 numeral 3. Metal sheathing 4 covers the extreme tip of each blade and extends along the leading edge nearly to the hub. The direction of the wind is downward against the upward shown flat faces of the blades 40 in Figure 1 and in the direction of the vertical arrows of Figure 2, 3, 4 and 5. The direction of rotation is indicated by the curved arrow of Figure 1 and by the horizontal arrows of Figures 4 and 5.

In plan form (Fig. 1) the blades are 45 decidedly curved from the hub outwardly, the curvature being opposite in direction from the direction of rotation so that each successive blade cross-section is somewhat rear- 50 wardly positioned with respect to the pre-

ceding cross-section, the tip of the blade being narrowest and most rearward of all. The leading edges and portions nearer them are decidedly thicker than the trailing edges and their corresponding portions as shown 55 in Figures 4 and 5 which are typical of sections throughout the blades. This gives the blades rigidity along their leading edges and relative flexibility along their trailing edges. An equal distribution of wind pressure across the blade would therefore cause greater deflection of the trailing than of the leading edge with increase of blade angle with respect to the plane of rotation but it happens that the greater part of the 60 wind pressure is nearly always nearer to the leading edge, thus tending to increase the deflection of the more rigid part of the blade perhaps as much or more than that of the thin trailing edge. However, this tendency 65 is much more than offset by the rearward curvature of blades above described. This curvature places the entire wind pressure at each cross-section at a more rearward position than at its preceding cross-section 70 (considered from the hub outwards). So great is the combined effect of curvature and relative flexibility at the trailing edge it is possible to so design and proportion the 75 blade that pressure at any point in the region of the outer half of the blade will cause an increase of all its angles with respect to the plane of rotation. The advantages of a windmill blade so designed are 80 very great in that the blade normally carries a relatively flat angle to facilitate easy starting and effective operation in winds of low velocity while with every increase of wind velocity the added pressure on the 85 blade causes it to take a position of greater angle to its plane of rotation with consequent greater torque or turning effect. The increased angularity of blade position under pressure of the wind is clearly shown by 90 dotted lines in Figures 2, 3, 4 and 5. The reverse changes of blade angle, of course, occur with decreasing wind. The ability to increase blade angles with increasing 95 wind and the reverse with decrease of wind enables this improved windmill blade to op- 100

erate with less fluctuation of rotational speed under varying winds and to deliver great increase of power from the higher winds without corresponding increase of rotational speed.

In order to obtain still greater change in the angles of the blades in response to changes in velocity of the wind I employ the further feature particularly illustrated 10 in Figure 2. Here it will be seen that the blades instead of lying radially in a flat plane of rotation are given an oblique position, the blades being set or bent in an axial direction and towards that side of the plane 15 of rotation on which lies the side of the blade receiving impact of the wind. As shown in the figures this places the flat sides of the blades at their extremities and outer portions in such position that a line connecting them passes clear of the hub on its windward side. In consequence of this oblique positioning of the blades centrifugal force acts upon them with a component in the same direction as the pressure of the wind, thus virtually adding to the pressure 20 of the wind on the flat sides of the blade. This causes still greater deflection of the trailing edges of the blades than the deflection caused by wind pressure alone with consequent further increase in blade angles, the 25 amount of this further increase depending upon the rotational speed. Thus it is seen that the curved plan form combined with the obliqueness of blade position results in a 30 combined action of wind pressure and centrifugal force both for increase of blade angles and consequent greater increase of torque with increasing wind. This adaptability of the windmill blades to overcome increasing torque resistances with increases of 35 speed is found of great service for driving apparatus in which the torque resistance increases rapidly with its rotational speed. This windmill blade is therefore peculiarly 40 adapted for driving electric generators, 45 both because of its facility for starting in low winds and for its ability to more rapidly increase its torque effect with increase of wind and rotational velocity.

Having thus described the invention, what is claimed as new and desired to be secured by Letters Patent is:

1. A windmill impeller having blades, each of said blades being flat on one side and convex on the other side, said blades having

an axial inclination towards that side of the plane of rotation on which lies the flat side of the blade.

2. A windmill impeller having blades, each of said blades being curved in a direction opposite from its direction of rotation and having an axial inclination towards that side of the plane of rotation on which lies the side of the blade receiving impact of the wind.

3. A windmill impeller having blades, said blades being curved in a direction opposite from their direction of rotation and having their leading edges relatively rigid and their trailing edges relatively flexible 80 and said blades having an axial inclination towards that side of the plane of rotation on which lies the side of the blade receiving impact of the wind.

4. A windmill impeller having blades, 85 said blades having leading edges and trailing edges, said edges being curved in a direction opposite from their direction of rotation and said leading edges being of greater curvature than said trailing edges 90 and said blades having an axial inclination towards that side of the plane of rotation on which lies the side of the blade receiving impact of the wind.

5. A windmill impeller having blades, 95 said blades having leading edges and trailing edges, said edges being curved in a direction opposite from their direction of rotation and said leading edges being of greater curvature and less flexibility than said 100 trailing edges and said blades having an axial inclination towards that side of the plane of rotation on which lies the side of the blade receiving impact of the wind.

6. A windmill impeller having blades, 105 said blades being formed of portions varying in flexibility, the said blades being axially inclined forwardly so that they will increase their face angularity in direct response to centrifugal force.

7. An impeller blade for windmills having its leading edge relatively rigid and its trailing edge relatively flexible, so that pressure of the wind causes greater deflection of the trailing edge of the blade, the longitudinal axis of said blade being inclined forwardly with respect to its plane of rotation, so that said blade will increase its face angularity in response to centrifugal force.
